UNITED STATES PATENT OFFICE.

WILLIAM F. RAY, OF CHICAGO, ILLINOIS.

TIRE OR INTERLINER STRUCTURE.

1,251,576.

Specification of Letters Patent. Patented Jan. 1, 1918.

Application filed July 20, 1917. Serial No. 181,694.

To all whom it may concern:

Be it known that I, WILLIAM F. RAY, a citizen of the United States, residing at Chicago, in the county of Cook and State 5 of Illinois, have invented a new and useful Tire or Interliner Structure, of which the following is a specification.

This invention relates particularly to pneumatic tires; and the primary object is 10 to provide a puncture-proof tire which shall be both resilient and durable.

It may be stated preliminarily that, in the preferred embodiment of my invention, I construct a puncture-proof inner casing, or 15 inter-liner, and then introduce the same within a casing of any well known construction, preferably cementing or vulcanizing the inter-liner to the inner surface of the main casing.

20 The invention is illustrated, in its preferred embodiment, in the accompanying drawings, in which—

Figure 1 represents a transverse sectional view of a development of my improved 25 inner casing, or inter-liner, the plies of material being shown separated for clearness of illustration, the section being taken as indicated at line 1—1 of Fig. 2; Fig. 2, a broken developed view of the improved 30 inter-liner; Fig. 3, a transverse sectional view of a casing having my improved inter-liner vulcanized therein, so as to form an integral part of the casing; and Fig. 4, a broken sectional perspective view, the section being taken as indicated at line 4 of 35 Fig. 3.

In the embodiment illustrated, A represents a tire casing, which may be of any well known construction; and B my improved 40 inter-liner, or inner casing, vulcanized to the inner surface of the outer or main casing A.

The casing A may be constructed of rubber and cotton fabric in the usual manner, which requires no detailed description. In Figs. 45 3 and 4, the full line 1 represents the line of junction between the outer casing A and the inner casing B.

The inner casing, or inter-liner B preferably comprises an outer-ply 2 of cotton 50 fabric, which extends circumferentially about the inter-liner and forms the outer surface thereof; a relatively narrow cir-

cumferential strip or thin ply of elastic rubber 3, which extends throughout the great circle of the inter-liner; a companion 55 strip or thin sheet of rubber 3^a of the same dimensions; an interposed series of transversely extending armor-elements, or anti-puncture elements, 4, which may comprise thin spring-steel strips adapted to be curved 60 transversely, and which extend transversely of the tire; a pair of narrow strips of fabric 5 extending circumferentially around the inter-liner parallel with the rubber strips 3 and 3^a, and flanking the same; a pair of 65 slightly wider strips of fabric 6 flanking the rubber strips 3 and 3^a and corresponding in thickness with said rubber strips and the interposed spring-steel plates 4; narrow strips of fabric 7 and 7^a, which extend transversely in the inter-liner and fill the spaces between the steel strips 4, as will be clearly 70 understood from Figs. 2 and 4; a ply of fabric 8, which extends throughout the great circumference of the inter-liner and 75 which is of slightly greater width than the combined width of the strips of fabric 6 and strips of rubber 3; a ply of fabric 9 of somewhat greater width; a pair of elastic rubber sheets or strips 10 and 10^a corresponding in width with the strips 3 and 3^a; a series of interposed spring-steel strips 11; a pair of fabric strips 12 of slightly greater 80 width than the strips 6; a pair of fabric strips 12 and a pair of fabric strips 13 85 flanking the rubber strips 10 and 10^a and the interposed steel strips 11; narrow strips of fabric 14 and 14^a filling the spaces between the steel strips 11; a ply of fabric 15, which is of greater width than the combined 90 width of the strips 13 and the interposed rubber strips 10 and 10^a; and an inner ply of fabric 16 of slightly greater width and which forms the inner surface of the inter-liner. The ply of fabric 16 is of slightly less 95 width than the outer ply 2; and it will be noted that the arrangement of all the plies and interposed steel strips is such as to form an inter-liner having a comparatively thick central or thread portion and tapering side 100 portions, as will be understood from Fig. 3.

The steel strips 4 may conveniently be about one inch in width, one-tenth of an inch thick, and about three inches long. The

dimensions may vary, of course, depending upon the size of the tire. The steel strips are resilient and they are preferably coated with a rubber compound and vulcanized, thus acquiring a hard rubber surface. The compound preferably is such that the strips will become vulcanized to the strips of rubber between which they are interposed, in the operation of vulcanizing the inter-liner. This is not indispensable, however, inasmuch as the fabric strips are all thoroughly vulcanized together, so that in any event the steel plates or puncture-proof elements will be firmly held in their embedded 15 position in the inter-liner.

The transverse spaces between the outer series of metal strips 4 are preferably of about one-half inch in width; and the inner steel strips 11 are correspondingly 20 spaced, but are staggered with relation to the outer series of plates. That is, the inner plates are disposed beneath the spaces between the outer plates, and the outer plates cover the spaces between the inner plates. 25 The steel plates or anti-puncture elements are desirably of sufficient length to guard against puncturing any portion of the tread of the tire which is liable to come in contact with a nail or other puncturing element.

30 The sheets and strips of fabric employed are all rubberized or thoroughly saturated with a solution of rubber; and after the inter-liner has been built up on a suitable core or mandrel, it is subjected to the usual vulcanization process, which gives to it a permanent contour corresponding with the inner surface of the outer casing. It will be understood that in the vulcanizing process, the transverse narrow fabric strips 7 and 7^a 35 and the corresponding fabric strips 14 and 14^a are thoroughly vulcanized to the plies of rubber between which they are interposed, which are, in turn, vulcanized to the adjoining sheets of fabric; and the sheets 40 and strips of fabric are also thoroughly vulcanized together throughout the portions flanking the extremities of the steel plates. Thus, the steel-plates, or armor-elements are firmly secured in their embedded positions, 45 and well anchored by the canvas or fabric, as well as by the adhesive or vulcanizing effect between the metal strips and the adjacent plies of rubber. Moreover, the resilient metal strips are everywhere embedded in 50 rubber, so that wearing action upon the canvas or fabric is obviated in the use of the tire.

55 The inter-liner B may be vulcanized within the casing A, or may simply be introduced and used without vulcanization, if desired. Where the inter-liner is to be vulcanized within a casing, this may be accomplished by softening the film of rubber at the inner surface of the casing, or by applying a rubber

solution to the inter-liner, and then effect- 65 ing vulcanization in the usual manner.

The improvement described not only renders the tire puncture-proof, but increases the longevity of the tire. Any preferred manner of embodying the invention in a tire 70 structure may be employed.

The foregoing detailed description has been given for clearness of understanding only, and no unnecessary limitation should be understood therefrom, but the appended 75 claims should be construed as broadly as permissible in view of the prior art.

What I regard as new and desire to secure by Letters Patent is:

1. A tire structure comprising a pair of 80 rubber strips extending through the great circumference of the structure, a series of interposed transversely extending resilient spaced steel strips having a vulcanized coating thereon, a second pair of similar rubber 85 strips, a second series of interposed resilient steel strips having a vulcanized coating thereon, covering the spaces between the strips of the first-mentioned series, fabric interposed between the pairs of rubber strips 90 and extending laterally beyond the same, circumferential fabric strips flanking each pair of rubber strips, and outer and inner plies of fabric enveloping the elements mentioned, the structure being suitably shaped 95 and vulcanized together.

2. A tire structure comprising a pair of elastic rubber strips, an interposed series of spaced, transversely extending resilient steel strips having a vulcanized coating thereon, 100 relatively narrow fabric strips flanking said rubber strips, and relatively wide fabric plies enveloping the elements mentioned, the structure being suitably shaped and vulcanized together.

3. A tire structure comprising resilient steel strips having a vulcanized coating thereon, thicknesses of elastic rubber between which said steel strips are interposed, and fabric plies enveloping said thickness of 110 rubber and interposed steel strips, the structure being suitably shaped and vulcanized together.

4. In a tire structure, an inter-liner, comprising an outer ply of fabric of a width corresponding with the transverse outer circumference of the inter-liner, a pair of elastic rubber sheets adjacent thereto and corresponding with the tread portion of the tire, a series of spaced, transverse resilient steel 115 strips interposed between the rubber sheets, said steel strips having a rubber compound vulcanized thereon, fabric strips in the spaces between said steel strips, circumferential fabric strips flanking the rubber strips, 120 fabric plies adjacent the inner rubber sheet and of greater width than the combined width of said rubber sheet and the flanking 125

fabric strips, a second pair of rubber sheets adjacent the inner ply of fabric, transverse resilient steel strips between said last-mentioned rubber sheets, said last-mentioned 5 steel strips having a rubber compound vulcanized thereon, fabric strips in the spaces between said second-mentioned steel strips,

fabric strips flanking said second-named pair of rubber strips, and an inner fabric strip of greater width than the rubber strips 10 and the flanking fabric strips, the structure being suitably shaped and vulcanized together.

WILLIAM F. RAY.
